UNITED STATES PATENT OFFICE.

GEORGE O. MILLER, OF NORTH TONAWANDA, NEW YORK, ASSIGNOR TO LOUIS A. KELSEY,
OF NORTH TONAWANDA, NEW YORK.

CAP FOR SEWER AND OTHER PIPES.

No. 907,159.

Specification of Letters Patent.

Patented Dec. 22, 1908.

Application filed June 4, 1907. Serial No. 377,155.

To all whom it may concern:

Be it known that I, GEORGE O. MILLER, residing at North Tonawanda, in the county of Niagara and State of New York, have 5 invented certain new and useful Improvements in Caps for Sewer and other Pipes, of which the following is a specification.

This invention relates to caps for sewer and other pipes, and it has for its object the 10 production of a simple inexpensive, and durable cap provided with convenient and effective means for attaching the same to pipes.

The invention consists in the construction, arrangement, and combination of parts 15 to be hereinafter described and particularly defined in the appended claims.

In the drawings,—Figure 1 is a central vertical section through my improved cap, 20 showing the same applied to a piece of pipe. Fig. 2 is a vertical section taken on line 2—2, Fig. 1. Fig. 3 is a transverse section taken on line 3—3 Fig. 1 looking up. Fig. 4 is a detached inverted perspective view of the 25 cap with the locking-bar removed. Fig. 5 is a detached perspective view of the locking-bar. Fig. 6 shows the application of my invention to a strainer cap.

Referring to the drawings in detail, similar numerals of reference refer to similar 30 parts in the several figures.

The reference numeral 1 designates a 35 ventilating pipe of a sewer system, having applied to its upper end my improved cap 2 which is adapted to be securely affixed while providing for the escape of foul gases from the ventilating pipe.

The cap is of ordinary formation; that is,—concavo convex in cross-section,—and it is 40 provided on its inner face with projections or webs 3 which bear against the upper edge of the pipe and serve to support the cap on the pipe, and with projections or webs 4 which fit outside of the pipe and serve to 45 center the cap on said pipe. This however, forms no part of my invention and may be varied to suit the desires of the producer.

Depending from the webs 3 are lugs 5 and 6; lug 5 being adapted to bear against 50 the inner face of the pipe, while lug 6 is separated from the wall of the pipe by a space

7 and has its outer face 8 inclined to form a tapering lug.

Passing centrally through the cap at the top thereof is a locking and adjusting screw 9 55 which is of considerable length and extends down between lugs 5 and 6. Said screw enters a threaded aperture 10 in a horizontally disposed lock bar 11 which has one end notched, as at 12, to form a bifurcated portion that straddles lug 5. Near its other end said bar has a rectangular aperture 13 with its outer end wall 14 beveled to correspond with the inclined face of lug 6, which latter enters said aperture. The lock-bar is guided 60 for vertical movement on lugs 5 and 6, and aperture 12 is made somewhat longer than the width of lug 6 so that on drawing the lock-bar upward when revolving the screw, is moved slightly in a longitudinal direction, 65 due to the beveled wall of aperture 12 acting against the inclined face of lug 6.

On drawing the lock-bar upward, that end in which the aperture 13 is formed, is wedged 70 securely against the inner face of the pipe 75 and causes lug 5 to impinge against the pipe at a point diametrically opposite. In this manner, a secure fastening is assured.

In Fig. 6, I have shown my cap in the form of a strainer-plate, the device being otherwise similar to that above described.

Having thus described my invention, what I claim is,—

1. A cap for pipes having depending lugs, and a single horizontal lock-bar guided for 85 combined vertical and longitudinal movement on said lugs, the lugs and lock-bar co-acting to cause the cap to be secured to a pipe when said lock-bar is moved on said lugs.

2. A cap for pipes having depending lugs, one of which is provided with an inclined edge, a screw passing through the top of said cap, a horizontal lock-bar carried by said screw and having an aperture near one end 95 into which fits the lug having the inclined edge, said lock-bar being adapted to move endwise against the inner surface of the pipe by contacting with the inclined edge of the lug when drawing said lock-bar upward.

3. A cap for pipes having opposite depending lugs, one of which has its outer edge in-

clined, a screw passing centrally through the cap, a horizontal lock-bar having a threaded aperture into which said screw is threaded and having also a notch at one end fitting one 5 of said lugs and an aperture at its other end provided with a beveled end wall bearing against the outer inclined edge of the other of said lugs.

In testimony whereof, I have affixed my signature in the presence of two subscribing 10 witnesses.

GEORGE O. MILLER.
